GRINDING METHOD AND APPARATUS

Hal F. Fruth, Chicago, Ill., assignor to Galvin Manufacturing Corporation, Chicago, Ill., a corporation of Illinois

Application July 14, 1943, Serial No. 494,681

11 Claims. (Cl. 51—73)

The present invention relates to improved grinding methods and apparatus and has for one of its objects the provision of improved methods and apparatus for grinding the rounded outer surfaces of an object.

It is another object of the invention to provide improved methods and apparatus for grinding the outer surfaces of small tubular objects or rings, such, for example, as piston rings, without abrading the edge or inner surfaces thereof.

According to another object of the invention, the abrading action is produced in an entirely random manner and the weight of each object alone determines the contact pressure between the abrasive surface and the surface being abraded.

In accordance with a further object of the invention, the random grinding of the surfaces to be abraded is enhanced by only intermittently moving the surfaces into engagement with the abrasive surface and by utilizing the relative movement between the abrading and abraded surfaces to change the segments of the abraded surfaces which are intermittently moved into engagement with the abrasive surface.

It is still another object of the invention to provide improved and exceedingly simple methods and apparatus for rapidly abrading the outer surfaces of relatively small tubular objects several at a time and with a minimum expenditure of manual labor.

It is a still further object of the invention to provide an improved grinding tube which is well adapted for use in the surface grinding of small objects.

The invention, both as to its organization and method of operation, together with further objects and advantages thereof, will best be understood by reference to the following specification taken in connection with the accompanying drawings, in which:

Fig. 1 is a side view partially in section of improved apparatus for grinding the rounded outer surfaces of small tubular objects, which is characterized by the features of the present invention;

Fig. 2 is a side view partially in section illustrating the details of the object holding assembly forming a part of the apparatus shown in Fig. 1;

Fig. 3 is an end sectional view of the assembly shown in Fig. 2;

Fig. 4 is an end sectional view illustrating the manner in which the objects are supported upon the holding assembly within the grinding tube forming a part of the apparatus;

Fig. 5 is a side view of an improved grinding

tube which may be utilized in conjunction with the apparatus shown in Fig. 1;

Fig. 6 is a side view of a modified object holding assembly;

5 Fig. 7 is an end view of the holding assembly shown in Fig. 6;

Fig. 8 is an end sectional view of the holding assembly shown in Fig. 6 illustrating the manner in which the objects are supported thereon; and

10 Fig. 9 is a detail view of one of the elements embodied in the assembly shown in Fig. 6.

Referring now to the drawings and more particularly to Figs. 1, 2, 3 and 4 thereof, the improved grinding apparatus there illustrated comprises a base 10 which rotatably supports an elongated grinding tube holder 11, slidably supports an object holder assembly indicated generally at 12, and rigidly supports an electric motor 13 having the function of rotating the grinding tube

15 holder 11. More specifically, the tube holder 11 is provided with a shaft 11b and comprises an elongated portion 11a having a tubular recess therein which is adapted to receive a grinding tube 14. The shaft 11b is suitably journaled in

20 bearings carried by upstanding bearing pedestals 15 and 16 which are rigidly supported upon the base 10. Sleeves 17 and 18, set screw mounted upon the shaft 11b of either side of the pedestal 15, may be employed for restraining the shaft 11b against axial movement relative to the two bearing pedestals 15 and 16. At its left end, the shaft 11b rigidly mounts a pulley 19 which is connected by means of a belt 20 to a driving pulley 21 carried by the rotor shaft of the motor 13.

25 As best shown in Figs. 2 and 3 of the drawings, the object holder 12 comprises an upstanding bracket 22 having an elongated base portion 22a which is provided with flared and ground edge surfaces 22b and 22c at opposite sides thereof.

30 The elongated flanged base portion 22a of the bracket 22 is adapted to be slidably received within a guide slot 23 machined longitudinally of the base 10 at the upper side thereof in alignment with the shaft 11b of the grinding tube holder 11.

35 This slot is provided with downwardly and outwardly flared bearing surfaces 23a and 23b which guidably engage the flared edge portions of the bracket base 22a. In the upstanding portion thereof, the bracket 22 is provided with an elongated vertically extending slot 24 for slidably receiving the extended bearing portion 25a of a motor and shaft supporting bracket 25. This bracket is provided with a horizontally extending base portion 25b upon which a small electric mo-

40 tor 26 is suitably mounted. Through the bearing

portion 25a thereof, the bracket piece 25 is bored to receive a shaft 27 which rigidly mounts an eccentrically arranged tube or ring supporting roller 28 at its left end. A sleeve 29 set screw mounted upon the right end portion of the shaft 27 may be utilized to restrain the shaft assembly against axial movement relative to the bracket piece 25. At its extreme right end, the shaft 27 mounts a pulley 30 which is connected in driven relationship with the motor driving pulley 31 by means of a belt 32. In order to maintain the bracket piece 25 and associated elements rigidly supported upon the bracket 22, assembly screws 33 and 34 and associated slots spanning bars 35 and 36 are provided. More specifically, the screws 33 and 34 are threaded into tapped holes drilled into the bracket piece 25 so that the heads thereof may be drawn into tight engagement with the adjacent surfaces of the spanning bars 35 and 36 when the two bars are positioned to span the slot 24 and to engage the face surfaces of the bracket 22. In order to facilitate the explanation pertaining to the operation of the apparatus, the eccentrically mounted roller 28 is illustrated as supporting a plurality of piston rings 37. The rings or another tubular object telescoped over the roller 28 are prevented from slipping off the end of the roller by a retaining plate 38, which is of greater diameter than the roller 28 and is concentrically mounted upon the end of the roller by means of assembly screws 39.

From the above description, it will be understood that the ring or tube holding assembly is readily adjustable longitudinally of the base 10 for the purpose of inserting the roller 28 within the grinding tube 14 and withdrawing the roller from this tube. Thus the loading and unloading of the roller with a desired number of piston rings, for example, is easily accomplished. The holding assembly 12 is also such that the roller 28 may be readily adjusted in a vertical direction relative to the axis of rotation of the grinding tube 14, whereby the apparatus may be readily adapted for the grinding of tubes or rings having different outside diameters.

The grinding tubes which are used in the apparatus may be of the improved form illustrated in Figs. 1 and 5 of the drawings. As there shown, the illustrated grinding tube 14 comprises a flexible backing material, formed of cloth or paper, 50 for example, which is coated at its inner surface with particles of a suitable grinding material. More specifically, the tube 14 may be formed by spirally edge winding an elongated strip of abrasively coated cloth and by suitably cementing 55 the abutting edges of the strip. In order to minimize variations in the thickness of the tube, occasioned by providing a connecting means for joining the abutting edges of the strip, the edges are preferably spliced by wrapping the tube as 60 formed from the spirally wound strip with wire cloth of small mesh and thin strands, and then pressing the strands of the wire cloth into the cloth backing material of the strip. When this splicing technique is employed, a tube of uniform 65 thickness and of rugged character is obtained. The character of the abrasive material with which the backing strip is coated depends, of course, upon the particular grinding operation which is to be performed. If relatively fast grinding is 70 desired, a tube coated with an abrasive material consisting of No. 220 screen mesh silicon carbide may be employed. On the other hand, if relatively slow grinding accompanied by a high polish of the ground surfaces are desired, a tube coated 75

with No. 320 screen mesh silicon carbide may be used. In this regard it will be understood that the particles of abrasive material may be affixed to the surface of the strip by means of a suitable cement or adhesive substance and by employing any of the coating methods conventionally practiced in the art. The grinding tube may also be formed by impregnating a length of copper tubing with grinding powder on the inner surface thereof. Alternatively, a grinding powder impregnated copper strip may be edge wound to form the tube. As a further alternative the tube may be formed of a moldable material having the abrasive material impregnated or molded into the inner surface thereof.

In utilizing the above-described apparatus to practice the present improved grinding methods, a grinding tube 14 having its inner surface coated with abrasive material of a size suitable to the grinding operation at hand is inserted within the hollow portion 11a of the holder 11, the relative dimensions of the two mentioned interengaging parts being such that the outer surface of the tube is in tight frictional engagement with the inner surface of the holding cup 11a. Assuming, for example, that the outer rounded bearing surfaces of a plurality of piston rings 37 are to be ground and polished, the holding assembly 12 is slid to the position illustrated in Fig. 1 of the drawings, following which the rings are telescoped over the retaining plate 38 and are left hanging suspended upon the roller 28, preferably with their adjacent edges in engagement. The assembly 12 is next slid longitudinally of the base 10 to project the roller 28 within the tube 14 and thus bring the lower surface of the rings 38 into a position for engaging the abrasively coated inner surface of the tube. The next operation is that of adjusting the vertical position of the bracket piece 25 and its associated elements relative to the bracket piece 22 so that when the section of the eccentrically mounted roller 28 of shortest radius overlies the shaft 27, the inner surfaces of the rings 37 are just out of engagement with the adjacent upper surface of the roller and the lower outer surface segments of the rings engage the abrasively coated inner surface of the tube 14. This may be accomplished by loosening the screws 33 and 34, adjusting the bracket piece 25 and its associated elements to the desired vertical position, and then retightening the named assembly screws to retain the bracket piece 25 in its adjusted position. It will be understood in this regard that once the position of the bracket piece 25 and the elements carried thereby is established, no further adjustment is necessary so long as rings or tubes of the same external diameter are to be ground. After the above-described adjustments have been made, operation of the motor 13 to rotate the grinding tube holder 11 and operation of the motor 26 to rotate the roller 28 may be initiated. In this regard it is noted that the motor 13 is arranged to drive the grinding tube holder 11 at a relatively high rate of speed, whereas the motor 26 is essentially a slow speed device and is arranged to drive the shaft 27 and roller 28 at a relatively slow rate of speed.

As best shown in Fig. 4 of the drawings, during that portion of each revolution of the roller 28 when the section of the roller of shortest radius is moving to overlie the shaft 27, the lowermost outer peripheral segments of the rings 37 are dropped into engagement with the abrasively coated inner surface of the grinding tube 14.

With the roller 28 in this position, the upper surface thereof is disengaged from the upper inner peripheral surfaces of the rings, so that the rings are wholly and completely supported upon the abrasively coated inner surface of the grinding tube. As the shaft 27 continues to rotate under the influence of the driving motor 26, the radius of the roller section which underlies the inner top surface segments of the rings steadily increases until the roller surface engages the inner ring surfaces, at which time the rings are again supported upon the roller 28. This support of the rings by the roller is maintained until such time as the decrease in radius of the roller supporting section again permits the outer peripheral surfaces of the rings to be brought into engagement with the inner surface of the grinding tube. It will thus be apparent that during the continuous rotation of the eccentrically mounted roller 28, the rings 37 are intermittently dropped into engagement and moved out of engagement with the abrasively coated inner surface of the grinding tube 14.

During at least a portion of each period when the outer peripheral surfaces of the rings engage the abrasive surface of the grinding tube, the rings are wholly and freely supported upon the grinding surface. Since this surface is traveling at a relatively high rate of linear speed, relative movement occurs between the abrading surface and the engaged peripheral surface segments of the ring, with the result that the surface segments of the rings are abraded and polished. Because of the frictional engagement between the rings and the abrasive surface of the grinding tube 14 during those short intervals when the rings are wholly supported upon this surface, the rings are spun at random about the roller 28. The extent of rotation of each ring is of course indeterminate and may vary widely as between different grinding intervals. Accordingly, during different and succeeding grinding periods, different peripheral surface segments of each ring are moved into engagement with the abrasive surface of the grinding tube 14. This insures that the peripheral surfaces of the rings will be ground entirely at random. On an average basis, however, and when the grinding action is allowed to proceed for a given time interval of reasonable length, all surface segments of each ring are abraded to substantially a uniform depth.

The random grinding of the ring surfaces is contributed to by the rotation of the eccentrically mounted roller 28. Thus, during each period when the rings are supported upon the roller out of engagement with the abrasive surface of the grinding tube 14, they are rotated through a given and fixed angle, thus insuring that during the next succeeding grinding interval different segments of the outer peripheral surfaces of the rings will be brought into engagement with the abrasive surface of the tube 14. After the rings have been ground to the desired thickness as determined by conventional methods of micrometer measurement or have been polished to the desired degree by utilizing a tube coated with an exceedingly fine abrading material, they may be removed from the holding assembly 12 in a manner which will be clearly apparent from the above explanation.

In grinding to a given thickness a batch of rings which have been selected at random, the rings may be measured as to thickness, and ground for a given time interval such that certain of the rings of the batch are brought substan-

tially to the desired thickness. The remaining rings, i. e. those initially having the greatest thickness, may be classified and subjected to further grinding for time intervals which may be calculated by correlating the grinding speed with the difference between the desired thickness and the actual thickness after the initial grinding operation is completed. In other words, following the initial grinding operation, the rings may be grouped according to the thickness thereof and those rings of each group may be subjected to a further grinding operation for an interval which is calculated from the difference between the actual and desired thicknesses as correlated with the speed at which the grinding action proceeds. In the secondary grinding operation, it may be desirable to use a grinding tube coated with abrasive particles having a substantially greater fineness than the particles of the tube initially used; in order that the secondary grinding operation may proceed at a less rapid rate and thus may be more accurately performed on a time basis.

The desired intermittent and random grinding of the rounded outer surfaces of tubular objects may also be obtained by utilizing the arrangement illustrated in Figs. 6, 7, 8 and 9 of the drawings for resiliently supporting the rings or tubes within the grinding tube 14. In this arrangement, which is of cage-like form, a retaining plate 40 is rigidly mounted upon an assembly plate 41 by means of three angularly spaced apart rods 42, 43 and 44 which extend parallel to each other and are rigidly secured to the two plates 40 and 41 at opposite ends thereof. The plate 41 is adapted to be rigidly and adjustably mounted upon the pedestal bracket 22 by means of assembly screws 45 and 46 which extend through the guide slot 24 of the bracket 22 and are threaded into the assembly plate 41. For the purpose of resiliently and directly supporting rings or short tubular parts upon the holder assembly, a flexible element 47 in the form of an elastic band or a coil spring of small diameter is stretched between the two plates 40 and 41 and suitably anchored to these plates at the opposite ends thereof. In order to prevent excessive wear and sagging of the elastic element 47, a tube 48 formed of metal, fiber or the like may be telescoped over the element to provide a bearing surface which engages the inner peripheral surfaces of the rings or tubes.

In the operation of the modified holder assembly to produce the desired random grinding of the ring or tube surfaces, the position of the assembly is vertically adjusted along the bracket 22 until the inner surfaces of the rings 37, for example, are partially supported by the tube 48 and resilient element 47 when the lower peripheral surface segments of the rings engage the abrasive surface of the grinding tube 14. In other words, the weight of the rings 37 is partially utilized to stretch the resilient element 47 to a deformed position which it would not occupy if the rings were not partially supported thereupon. With the ring holding assembly adjusted to the vertical position just described and during rotation of the grinding tube 14 under the influence of the driving motor 13, the outer peripheral surfaces of the rings 37 are continuously moved intermittently and at random into engagement with the abrasive surface of the grinding tube. In this case, the inherent irregularities, namely, the hills and valleys, in the abrasive surface of the grinding tube employed, are utilized

to move the rings 37 up and down and thus produce oscillation of the resiliently supported tube 48. As oscillation of this tube is set up, the rings 37 are actually bounced into and out of engagement with the abrasive surface of the grinding tube so that complete random grinding action of the outer ring surfaces is obtained. In other words, an oscillatory mechanical system is provided, the oscillation of which is initiated and maintained by the surface irregularities of the abrasively coated inner surface of the grinding tube. The desired up and down movement of the rings into and out of engagement with the abrasive surface of the grinding tube is of course maintained so long as the grinding tube continues to rotate under the driving force of the motor 13.

From the above explanation, it will be understood that in accordance with the present invention improved methods and apparatus have been provided for obtaining complete random grinding of the rounded outer surfaces of rings or tubular articles. The material from which such articles are constructed is of no importance since abrading materials are available in granular form and suitable for coating the inner surfaces of the grinding ring, which will cut the surfaces of parts or articles formed of metal, glass, stone, quartz or practically any other material in commercial use. It will also be apparent that the grinding operations are fully automatic in character when once started and, accordingly, that a minimum of labor is involved in grinding and polishing the surfaces of a given number of articles. Further, the methods and apparatus are particularly well adapted for use in the grinding of relatively narrow or short tubular objects such as piston rings, which, when stood on edge, have a tendency to topple over and hence are not adapted to centerless grinding methods. In this regard, it will be observed from the above explanation that the random grinding action is produced solely at the outer peripheral surfaces of the rings with absolutely no edge grinding thereof. This feature of the invention is of extreme importance in the grinding of piston rings, wherein the edges are precisely machined to exact dimensions and are provided with polished surfaces which must not be scratched or otherwise marred during the peripheral surface grinding operations.

While different embodiments of the invention have been disclosed, it will be understood that various modifications may be made therein, which are within the true spirit and scope of the invention.

I claim:

1. The method of grinding the rounded outer surface of an object, which comprises continuously moving said object so that the rounded surface thereof intermittently engages an abrasive surface, producing relative movement between said abrasive surface and said rounded surface, and utilizing the frictional engagement between said abrasive surface and the engaging surface of said object continuously to change at random the segments of said rounded surface which are intermittently moved into engagement with said abrasive surface.

2. The method of grinding the rounded surface of an object, which comprises intermittently moving said surface and an abrasive surface into engagement, producing relative movement between said abrasive surface and said rounded surface, and utilizing the frictional engagement between said object and said abrasive surface to change at random the segments of said rounded

surface which contact said abrasive surface as said rounded surface and said abrasive surface are intermittently moved into engagement.

3. The method of grinding the surface of a round object, which comprises continuously raising and lowering said object so that the lower surface segment thereof is intermittently brought to bear against an abrasive surface, producing relative movement between said abrasive surface and the engaging segment of said rounded surface, and utilizing the frictional engagement between said abrasive surface and the engaging surface of said object continuously to change at random the segments of said rounded surface which are intermittently moved into engagement with said abrasive surface.

4. The method of grinding the rounded surface of an object, which comprises continuously bouncing said object upon a continuously moving abrasive surface with said rounded surface engaging said abrasive surface during each bounce cycle, and utilizing the frictional engagement between said abrasive surface and the engaging surface of said object continuously to change at random the segments of said rounded surface which are intermittently moved into engagement with said abrasive surface.

5. The method of grinding the rounded outer surface of an object, which comprises intermittently bringing said rounded surface and a continuously moving abrasive surface into engagement, and utilizing the frictional engagement between said abrasive and rounded surfaces continuously to change at random the segments of said rounded surface which are intermittently engaged by said abrasive surface.

6. The method of grinding the rounded outer surface of an object, which comprises intermittently bringing said rounded surface and an abrasive surface into engagement, producing relative movement between the engaging abrasive and rounded surfaces, and utilizing the frictional engagement between said abrasive and rounded surfaces continuously to change at random the segments of said rounded surface which are intermittently engaged by said abrasive surface.

7. The method of grinding the outer rounded surface of a resiliently supported object, which comprises positioning said object so that a surface segment thereof engages an abrasive surface, continuously moving said abrasive surface relative to said object, and utilizing the irregularities of said abrasive surface to produce oscillation of the resilient structure supporting said object, whereby different surface segments of said rounded surface are intermittently moved into engagement with said abrasive surface.

8. Apparatus for grinding the outer surface of a round object comprising, in combination, an endless abrasive surface, means for continuously moving said surface, means for continuously moving said object so that the outer surface thereof is intermittently moved into engagement with said abrasive surface and means supporting said object so that the frictional engagement between said abrasive and outer surfaces causes the segments of said outer surface which intermittently engage said abrasive surface to be changed at random.

9. Apparatus for grinding the outer surface of a round object comprising, in combination, a tubular member provided with an abrasively coated inner surface, means for rotating said member about its axial center, means supporting said object within said tubular member,

and means for continuously moving said object so that the outer surface thereof is intermittently moved into engagement with the abrasively coated inner surface of said tubular member.

10. Apparatus for grinding the outer surface of a round object comprising, in combination, a tubular member provided with an abrasively coated inner surface, means for rotating said member about its axial center, and resilient means loosely supporting said object within said tubular member so that segments of the outer surface of said object may be continuously bounced into and out of engagement with the abrasively coated inner surface of said tubular

10
15

member during rotation of said tubular member.

11. Apparatus for grinding the rounded surface of an object comprising, in combination, an abrasive surface, means for alternately moving said rounded surface and abrasive surface into and out of engagement, means for producing relative movement between said surfaces when engaged, and resilient means supporting said object for bouncing engagement with said abrasive surface so that the intermittent frictional engagement between said surfaces causes the segments of said rounded surface which intermittently contact said abrasive surface to be changed at random.

HAL F. FRUTH.
